UNITED STATES PATENT OFFICE.

HALLEY C. DOLAN, OF DETROIT, MICHIGAN.

SIGNAL.

1,182,656.

Specification of Letters Patent.

Patented May 9, 1916.

Application filed April 26, 1915. Serial No. 24,114.

To all whom it may concern:

Be it known that I, HALLEY C. DOLAN, a citizen of the United States of America, residing at Detroit, in the county of Wayne and State of Michigan, have invented certain new and useful Improvements in Signals, of which the following is a specification, reference being had therein to the accompanying drawings.

10 This invention relates to an automobile traffic signal and the principal object of my invention is to provide an electrically operated signal which will indicate by day, as well as by night, to oncoming vehicles, the 15 fact that the signal carrying vehicle is about to stop, reduce speed, or turn into another lane of travel.

20 A further object of this invention is to provide a strong and durable signal embodying movable arms for indicating direction of travel, shutters controlling the display of visible signs, and the electrical devices for moving the arms and shutters, said electrical devices being controlled from the chauffeur's 25 seat of an automobile.

The above and other objects are attained by a mechanical construction that will be hereinafter specifically described and then claimed, and reference will now be had to 30 the drawings, wherein—

35 Figure 1 is a front elevation of the traffic signal, showing one of the signal arms in an extended or active position; Fig. 2 is a horizontal sectional view of the signal; Fig. 40 3 is a diagrammatic view illustrating electrical connections; Fig. 4 is a front elevation of part of the traffic signal with a portion thereof in section; and Fig. 5 is a longitudinal view of the signal, taken on the line V—V of Fig. 4.

In describing my invention by aid of the 45 views above referred to, I desire to point out that the same are intended as merely illustrative of an example whereby my invention may be applied in practice, and I do not intend to limit my invention to the precise construction shown. The following description is therefore to be broadly construed as including substitute constructions and arrangements of parts, which are the obvious equivalents of those to be hereinafter referred to.

The signal for the rear end of an automobile is in the form of a rectangular casing 55 having a rear wall 1, side walls 2 and 3, a bottom wall 4, a top wall 5, and a detachable

front wall 6, said detachable front wall being held upon the casing by screws 7 or other fastening means. The front wall 6 has the lower end thereof provided with an opening 60 in which there is mounted a holder 8 for a bull's eye or lens 9 and rays of light are cast through the bull's eye 9 by an incandescent lamp 10 carried by the bottom wall 4 of the casing. Associated with the incandescent lamp 10 are reflectors 11 and a vertical partition 12, said partition coöperating with the reflectors 11 in concentrating rays of light at the bull's eye 9. The partition 12 also coöperates with the bottom wall 70 4 of the casing in supporting the reflectors 11 and said partition has the upper and lower ends thereof suitably connected to the top and bottom walls 5 and 4 of the casing, as best shown in Fig. 5. The side edges of 75 the partition 12 are slotted and bent to provide reflectors 13 and these reflectors are adapted to cast rays of light in the direction of transparent plates 14, 15 and 16 mounted in a plate holder 17 supported by a strap 18 80 at an opening 19 in the front wall 6 of the casing.

The plates 14 and 15 are painted or otherwise treated to render portions thereof opaque, the remaining portions being transparent and arrow shaped as shown in Fig. 1, with the arrows pointing in opposite direction. The plate 16 is painted or otherwise treated to render portions thereof opaque with the remaining portions transparent and representing the characters of 85 the word "Stop". The plates 14, 15 and 16 constitute visible signs capable of being illuminated and displayed at night.

The inner sides of the walls 2 and 3 and the bottom wall 4 are provided with bearings 20 and 21, said bearings vertically alining contiguous to the front wall 6 of the casing. Journalized in these bearings are crank shafts 22 and 23, the former being of 100 a greater height than the latter for a purpose that will be hereinafter appear. The shafts 22 and 23 have crank portions 24 adjacent the lower ends thereof and engaging these crank portions are the ends of armatures 25 fulcrumed, as at 26 in frames 27 upon the bottom wall 4 and rearwardly of the partition 12. The frames 27 support electromagnets 28 and when said electromagnets are energized the rear ends of the 110 armatures 25 are attracted and impart movement to the shafts 22 and 23. The

armatures 25 extend through openings provided therefor in the frames 27 and the partition 12.

The lower ends of the shafts 22 and 23 are encircled by coiled retractile springs 29 and these springs retain the crank portions 24 of said shafts in engagement with the armatures 25 and restore said shaft to normal position after having been actuated. The upper ends of the shafts 22 and 23 have cranks 30 extending into slots 31 of members 32 and 33 horizontally disposed upon the bearings 21 and pivotally held in engagement therewith by screws 33^a or other pivotal means. The members 32 and 33 extend through slots 34 in the side walls 2 and 3, said members having lateral extensions 35 normally closing the slots. The outer ends of the members 32 and 33 are provided with right angularly disposed arms 36 having the outline of an arrow or spear. These arms are normally held in parallelism with the side walls 2 and 3 of the casing, said arms projecting rearwardly, as best shown in Fig. 2. The inner ends of the members 32 and 33 are provided with lateral extensions 37 and 38, respectively, said lateral extension engaging shutters 39 and 40 suspended from transverse rods 41, carried by the sides of the strap 18. The shutters 39 and 40 are at the inner sides of the transparent plate 15 and 14 respectively, and said shutters have the inner sides thereof provided with curved arms 42 normally engaged by the lateral extensions 37 and 38 of the horizontally disposed arm members 32 and 33.

Associated with the transparent plate 16 is an angularly disposed shutter 43 pivoted upon a rod 44 connecting the reflector 13 of the partition 12. The shutter 43 is supported by a crank 45 of a rock shaft 46, journaled in the sides of the strap 18. The rock shaft 46 has another crank 47 engaged by the forward end of an armature 48, said armature extending through an opening 49 in the vertically disposed partition 12. The armature 48 is fulcrumed as at 50 upon a frame 51, carried by a bracket 52, secured to the rear wall 1 of the casing. The frame 51 has an electromagnet 53 and when this magnet is energized, the armature 48 is attracted and through the medium of the rock shaft 46 and its crank, the shutter 43 is elevated, thereby exposing the transparent plate 16 to rays of light from the incandescent lamp 10. Otherwise the transparent plate 16 is cut off from the lower part of the casing and it is impossible for the rays of light to penetrate the shutter 43.

The rear wall 1 of the casing has the outer side thereof provided with a socket member 54 as an example, of a fastening means for securing the signal casing to the rear end of an automobile or other vehicle. The bot-

tom wall 4 of the signal casing has binding posts 55 and by reference to Fig. 3 of the drawings, it will be observed that a suitable source of electrical energy, as battery cells 56 and push buttons 57, 58 and 59 are electrically connected with the three electromagnets within the signal casing. The push buttons 57, 58 and 59 control the three circuits of the signal and as an instance of a circuit controlling the operation of the "stop" shutter 43, the push button 58 is connected to the electromagnet 53 by a wire 60, the electromagnet connected by a wire 61 to the battery cells 56, and the battery cells 56 by wires 62 and 63 to the push button 58.

Assuming that one of the other push buttons is pressed to close a circuit and energize one of the electromagnets 28, the armature 25 of the electromagnet is attracted and one of the vertically disposed crank shafts 22 or 23 is actuated. Further assuming that the shaft 22 is actuated, the member 32 at the upper end of the shaft is swung in a lateral plane into the casing, thereby swinging the arm 36 forwardly at right angles to the wall 2 of the casing, positioning the arm as shown in dotted lines of Fig. 2. Simultaneous with this operation the extension 37 of the member 32 shifts the arm 42 of the shutter 39, elevating said shutter and exposing the transparent plate 16 to rays of light emitted by the incandescent lamp 10. It is to be noted that when the shutter 39 is closed that the lateral extension 37 engages the inner side of the frame, as shown in Fig. 2, thereby preventing the shutter from accidentally moving or rattling. This is also true in connection with the shutter 40 and since the shutter 43 rests upon the crank 45 and closes by gravity, there is little danger of this shutter accidentally opening.

What I claim is:

1. In an automobile traffic signal, a casing, translucent signs carried thereby, shutters in said casing movable to and from said signs, arms at the outer sides of said casing movable relative to said casing and having members in said casing adapted to open said shutters, and electrical devices in said casing adapted to move the members of said arms.
2. In an automobile traffic signal, a casing, signs carried thereby, shutters in said casing movable to and from said signs, rearwardly extending arms in parallelism with the side walls of said casing movable relative to said casing and adapted to open said shutters, vertically disposed shafts in said casing for moving said arms, and electrical devices within said casing adapted to move said shafts.
3. In an automobile traffic signal, a casing, members pivotally mounted in said cas-

- ing and extending through the side walls thereof, arms carried by said members, signs forming part of said casing, shutters at the inner sides of said sign and held normally 5 in parallelism therewith by said members, means carried by said shutters and engaged by said members whereby said shutters can be opened, and means including shafts adapted to actuate said members whereby 10 said arms and shutters are simultaneously moved.
4. In a signal, a casing having a sign, a shutter in said casing movable to and from said sign, an arm normally outside of said 15 casing having a lateral extension in said casing normally engaging said shutter to hold the same in a closed position, means on said shutter normally engaging the extension of said arm and adapted to be moved thereby, and means in said casing adapted 20 to move said arm whereby said extension engaging means moves said shutter.
5. In a signal, a casing having a sign, a shutter in said casing movable to and from
- 5 said sign, an arm normally outside of said 25 casing having a lateral extension in said casing normally engaging said shutter to hold the same in a closed position, means on said shutter movable by the extension of said arm, and electrical means in said casing 30 including a crank shaft adapted to move said arm and impart movement to said shutter.
6. In a signal, a casing having a slot, a rearwardly extending arm at the outer side 35 of said casing, a member extending through the slot of said casing and connected to said arm, a lateral extension on said member normally closing the slot of said casing, and means in said casing engaging said member 40 and adapted to impart movement to said arm.

In testimony whereof I affix my signature in presence of two witnesses.

HALLEY C. DOLAN.
